[57] CLAIM

The ornamental design for a color selection chart, as shown and described.

DESCRIPTION

FIG. 1 is a top plan view of a color selection chart showing my new design;

FIG. 2 is a side elevational view, all other sides being identical thereto;

FIG. 3 is a bottom plan view thereof; and,

FIG. 4 is a top perspective view thereof.

*Fig. 1**Fig. 2**Fig. 3*

Fig. 4
